UNITED STATES PATENT OFFICE.

LEWIS C. HUNTER, OF DETROIT, MICHIGAN.

BED.

1,113,996.

Specification of Letters Patent.

Patented Oct. 20, 1914.

Application filed January 24, 1914. Serial No. 814,025.

To all whom it may concern:

Be it known that I, LEWIS C. HUNTER, a citizen of the United States of America, residing at Detroit, in the county of Wayne 5 and State of Michigan, have invented certain new and useful Improvements in Beds, of which the following is a specification, reference being had therein to the accompanying drawings.

10 This invention relates to beds, couches and structures used for sleeping purposes, and the primary object of my invention is to provide a bed structure that can be folded into an alcove, recess or compartment of a 15 wall, whereby it will present a neat appearance and allow floor space to be used for other purposes.

Another object of this invention is to provide a wall bed structure that can be easily 20 and quickly placed in position for use and swung at a desired angle relatively to its support for the convenience of the user.

A further object of this invention is to provide a metallic bed structure consisting 25 of comparatively few parts that are easy to assemble, strong and durable, and highly efficient for the purposes for which they are intended.

With the above and other objects in view, 30 the invention resides in the novel construction, combination and arrangement of parts to be hereinafter specifically described and then claimed.

Reference will now be had to the drawings, wherein—

Figure 1 is a plan of the bed in an extended position; Fig. 2 is a side elevation of the same in an upright folded position housed by a wall; Fig. 3 is a side elevation 40 of the bed in an extended position and partly broken away and partly in section; Fig. 4 is a perspective view of a portion of one of the rails of the bed; Fig. 5 is an enlarged longitudinal sectional view of a portion of a bed, illustrating a swivel; Fig. 6 is a side elevation of a modified form of bed; Fig. 7 is an enlarged cross sectional view of a portion of the same; Fig. 8 is a 45 front elevation of a portion of a panel or mirror adapted to form part of the bed; Fig. 9 is a side elevation of a portion of the bed, illustrating a further modification of my invention; Fig. 10 is an enlarged cross sectional view of the same, taken on the line X-X of Fig. 9; Fig. 11 is an end view of 50 the swivel shown in Fig. 5; and Fig. 12 is a

side elevation illustrating the telescopic portion of the mirror or panel shown in Figs. 6 and 8.

A bed structure in accordance with my 60 invention comprises substantial tubular uprights 1 provided with webbed feet 2, said uprights and the feet thereof constituting the base or head support of the bed structure. The upper ends of the uprights 1 are 65 bifurcated or slotted, as at 3, the slots extending to the feet of the uprights upon one side thereof in order to provide for the side arms 4 of a transverse brace 5. The side arms 4 are pivotally mounted in the upper 70 ends of the uprights 1 by transverse bolts 6 or other pivotal means, and the brace 5 of said side arms constitutes a weight to counter-balance and facilitate adjusting the bed structure.

75 Suitably secured upon the side arms 4 and extending outwardly therefrom are longitudinal parallel channel members 7 connected, intermediate their ends, by transverse parallel angle bars 8. Revolubly 80 mounted in the channel bars are a plurality of spaced anti-frictional rollers 9 that extend above the sides of said members and movably support a bed frame, comprising side rails 10, head and foot rails 11, and 85 head and foot pieces 12. The rails 10 and 11 are preferably made of angle bars and the head and foot rails 11 are adapted to support a conventional form of bed spring 13.

90 The bed frame can be shifted longitudinally of the members 7 and the inner ends of said members are provided with guards 14 adapted to over-hang the side rails 10 of the bed frame, when said frame is in a retracted position, and prevent lateral displacement of said frame. The transverse brace 5 has the ends thereof recessed or provided with sockets 15 to receive the ends of the side rails 10 when the bed frame is in a 95 retracted position. The side rails 10 have the outer ends thereof provided with depending guards 16 that ride into engagement with the members 7 when the bed frame is placed in a retracted position. 100 The guide rails 10 of the bed frame, intermediate their ends, are connected by transverse parallel angle bars 17 and riveted or otherwise connected to said bars is a plate 18 provided with a depending tapering 105 tongue 19. The tapering tongue 19 is dovetailed, as at 20 and said tongue is adapted to 110

engage in a tapering dove-tailed socket 21, whereby said tongue cannot become vertically displaced relatively to the socket 21. The socket 21 is carried by a plate 22 revolvably mounted upon a plate 23, carried by the transverse angle bars 8 connecting the members 7. This construction is best shown in Figs. 5 and 11 where it will be observed that the confronting faces of the plates 22 and 23 are provided with ball races for anti-frictional balls 24. The plates 22 and 23 are circular in plan and the plate 22 is revolvably supported relatively to the plate 23 by a screw bolt 25. The plates 22 and 23 constitute a turn table or swivel for the bed frame, and after the bed frame has been shifted to an extended position, with the guards 16 out of engagement with the supports 7 and consequently the side rails 10 out of engagement with the guards 14, the bed frame can be swung in a horizontal plane at an angle relatively to the supports 7.

To prevent the tongue 19 from becoming accidentally displaced relatively to the socket 21, when the bed frame has been swung out of alinement with the supports 7, the plate 23 is provided with inclined ways 44 and supported by said plate is a roller 45 having a spindle 46. The roller 45 extends into a slot 47 provided therefore in the plate 22, and said roller is retained in engagement with the plates by a strike plate 48 secured upon the plate 22. When the bed frame is swung out of alinement with the supports 7, the roller 45 rides up one of the ways 44 onto the plate 23 and consequently projects through the slotted strike plate 48 behind the tongue 19, said roller locking the tongue within the socket 21. The bed frame cannot therefore become accidentally displaced relatively to the swivel of the supports 7.

The side rails 10 of the bed frame have the outer ends thereof provided with pivoted legs 26 that can be swung into parallelism with the side rails 10, when the bed frame is placed in a retracted position.

The outer ends of the supports 7 are connected by side pieces 27 to a panel or mirror 28 that has the opposite end thereof supported by the side arms 4 of the transverse brace 5. Pivotaly connected to the side pieces 27 are legs 29 and these legs are adapted to coöperate with the legs 26 in supporting the bed structure in a horizontal position.

As illustrated in Figs. 1, 2 and 3, the uprights 1 are located in an alcove, recess or compartment 30 of a wall, said compartment being of sufficient size to accommodate the bed structure when swung to a vertical position, which can be accomplished by placing the bed frame in a retracted position with the legs 26 and 29 folded. In

front of the uprights 1 there is located a panel or wainscoting 31 which closes the lower part of the compartment 30 and the other part of said compartment is adapted to be closed by the panel or mirror 28 carried by the bed structure. It is therefore impossible to detect the presence of the bed structure when the compartment 30 is closed.

Reference will now be had to Figs. 6, 7, 8 and 12, illustrating a modification of my invention. The uprights 1 are provided with channel side arms 32 having revoluble rollers 33. Movable supported upon the rollers 33 is a bed frame 34 and the inner end of said bed frame has depending hangars 35 that engage under the side arms 32 and prevent the bed frame 34 from becoming accidentally displaced relatively to the side arms. The bed frame 34 can be easily shifted to a retracted position, whereby the bed structure can be swung to a vertical position in the compartment. In this instance, the side arms 32 support a mirror or panel 36 having a telescopic extension 37 which is connected to the outer end of the bed frame 34. Sections or portions of the frame forming part of the mirror panel provide legs 38, which can be easily and quickly swung into position to support the outer end of the bed structure when the same is lowered to a horizontal position.

A further modification of my invention is illustrated in Figs. 9 and 10, wherein side arms 39 are provided with semi-cylindrical rails 40 supporting anti-frictional balls 41. Movable upon the balls 41 are tubular side rails 42 of a bed frame, said side rails being held relatively to the rails 10 of the side arms by straps 43, carried by the side arms 39 and coöperating with the socket of the transverse brace of said side arms in preventing the tubular rails 42 of the bed frame from becoming accidentally displaced.

From the foregoing it will be observed that I have devised a novel bed structure that can be advantageously used in small rooms or compartments, especially where the room or compartment is used for other purposes than sleeping. It is possible to quickly swing the bed structure into a horizontal position, whereby it can be safely used, and the weight connecting the side arms of the structure is adapted to facilitate raising and placing the bed in a vertical position within the compartment 30. It will also be understood that the structure may be arranged in a like manner to fold sidewise instead of edgewise as shown where the wall space is adapted for such an arrangement and where so arranged the bed may be lowered, then pulled out laterally and turned to the desired position. A single upright or pedestal may be used in lieu of the uprights 1, and while in the drawings there are illustrated the preferred embodi-

ments of my invention, it is to be understood that the structural elements are susceptible to such changes in the shape, proportion and manner of assemblage, as fall within the scope of the appended claims.

5 What I claim is:—

1. A bed structure comprising uprights, connected arms pivotally supported by said uprights, longitudinal supports carried by said arms, a bed frame shiftable longitudinally of said supports, and inter-locking means between said bed frame and said supports whereby said bed frame can be swung in a horizontal plane at an angle to 10 said supports.

15 2. A bed structure comprising uprights, side arms pivotally mounted in the upper ends of said uprights, a bed frame movably supported from said side arms and capable of shifting longitudinally thereof, and means in connection with said bed frame and said arms for preventing said frame from becoming accidentally displaced.

25 3. A bed structure comprising uprights, side arms pivotally supported thereby, a bed frame movable longitudinally of said side arms, means carried by the inner ends of said bed frame to prevent the same from becoming accidentally displaced relatively to said side arms, and means carried by the outer end of said bed frame for supporting said frame in a horizontal position.

4. A bed structure comprising uprights, 35 arms pivotally supported thereby, a bed frame movable longitudinally of said arms, means carried by the outer end of said bed frame for supporting the same in a horizontal position, and means carried by said arms to facilitate swinging said bed frame to a vertical position.

5. A bed structure comprising uprights, side arms pivotally supported thereby, supports carried by said side arms, a bed frame 45 movable upon said supports, means carried by the outer ends of said supports and cooperating with said uprights in supporting said bed frame in a horizontal position, and means carried by said side arms to facilitate 50 swinging said bed structure to a vertical position.

6. A bed structure comprising uprights, side arms pivotally supported by said uprights, supports carried by said side arms, a 55 bed frame movable upon said supports, means carried by said side arms and said supports for limiting the movement of said bed frame thereon, and means carried by the outer ends of said supports and co-60 operating with said uprights in retaining said supports and said bed frame in a horizontal position.

7. In a bed structure, supports capable of 65 being swung from a horizontal to a vertical position, a bed frame movable upon said

supports, and inter-locking means between said supports and said bed frame whereby said bed frame can be swung in a horizontal plane relatively to said supports.

8. In a bed structure, supports capable of 70 being swung from a horizontal to a vertical position, a bed frame movable upon said supports and capable of being swung in a horizontal plane relatively to said support, and means in connection with said supports and said bed frame for retaining said bed frame in engagement with said supports when the same are in a vertical position.

75 9. In a bed structure, arms capable of being swung from a horizontal to a vertical position, a bed frame movable longitudinally of said arm, and means in connection with said bed frame and said arms for limiting the longitudinal movement of said bed frame relatively to said arms.

80 10. A bed structure comprising uprights, supporting arms carried thereby and capable of being swung from a horizontal to a vertical position, supports carried by said arms, a bed frame movable longitudinally of said supports, a swivel carried by said supports and provided with a socket, and a tongue carried by said bed frame and adapted to enter the socket of said swivel, whereby said bed frame can be swung in a horizontal 85 plane relatively to said supports.

90 11. A bed structure comprising uprights, supporting arms carried thereby and capable of being swung from a horizontal to a vertical position, supports carried by said arms, a bed frame movable longitudinally of said supports, a swivel carried by said supports and provided with a socket, and a tongue carried by said bed frame and adapted to enter the socket of said swivel, whereby said bed frame can be swung in a horizontal 95 plane relatively to said supports.

100 12. In a bed structure, the combination with a wall having a recess formed therein, of uprights arranged in the recess of said wall, supports carried by said uprights and capable of being swung from a horizontal position to a vertical position within the recess of said wall, a bed frame movable upon said supports, and means in connection with said supports for closing the upper part of said recess when said supports are 105 in a vertical position.

115 13. In a bed structure, the combination of supports capable of being swung from a horizontal to a vertical position, a swivel carried by said supports, a socket forming part of said swivel, a bed frame movable above said supports and capable of being swung in a horizontal plane relatively thereto, a tongue carried by said bed frame and adapted to engage in said socket, and means 120 125 130

in connection with said swivel for preventing said tongue from becoming accidentally displaced relatively to said socket.

14. In a bed structure, supports capable of being swung from a horizontal to a vertical position, a bed frame swiveled upon said supports intermediate the ends thereof and adapted to be swung in a horizontal plane, means to facilitate swinging said supports from a horizontal to a vertical position, and means in connection with said bed frame to prevent said bed frame from swinging relatively to said supports during a movement thereof.

15. 15. A bed structure comprising supports capable of being swung from a horizontal to a vertical position, a bed frame movable upon said supports, a swivel carried by said supports, a connection between said swivel and said bed frame whereby said bed frame can be swung in a horizontal plane relatively to said supports, and means in connection with said supports and coöperating with the connection between said swivel and said bed frame in preventing said bed frame from becoming accidentally displaced as said supports are swung to a vertical position.

16. The combination with supports, of a swivel carried thereby, a socket forming part of said swivel, a bed frame, a depending tongue carried thereby and adapted to

engage in said socket whereby said bed frame can be swung in a horizontal plane, and means in connection with said swivel 35 for locking said tongue within said socket when said bed frame is swung out of alignment with said supports.

17. A bed structure comprising supports capable of being swung from a horizontal to 40 a vertical position, and a bed frame swiveled upon said supports intermediate the ends thereof and adapted to swing in a horizontal plane.

18. A bed structure comprising supports 45 capable of being swung from a horizontal to a vertical position, a bed frame swiveled upon said supports, and means adapted to automatically lock said bed frame against longitudinal displacement relatively to said 50 support.

19. In a bed structure, supports, a bed frame, a swivel connecting said bed frame to said supports, said swivel having separatable members, and means in connection with said 55 bed frame for retaining said frame upon said supports when the members of said swivel are separated.

In testimony whereof I affix my signature in presence of two witnesses.

LEWIS C. HUNTER.
